ATTORNEYS.

UNITED STATES PATENT OFFICE

SAHN K. LOWE, OF HONOLULU, TERRITORY OF HAWAII

LIGHTING DEVICE

Application filed April 10, 1931. Serial No. 529,199.

This invention relates to improvements in lighting devices and has particular reference to means for lighting the side of a motor vehicle whereby the signalling arm of the driver will be readily visible from points in front or in the rear of the vehicle.

A further object is to produce a device of this character wherein the lights will be entirely protected from coming into contact with obstructions or being knocked against, as well as from weather elements, by being disposed into suitably covered pockets arranged in the fenders at or adjacent to their juncture with the running board of the vehicle.

A further object is to produce a device wherein the rays of illumination will not be blinding to either the driver of the vehicle or to the driver of any other vehicle approaching the machine.

Other objects and advantages will be apparent during the course of the following description.

In the accompanying drawing forming a part of this specification and in which like numerals are employed to designate like parts throughout the same,

The figure is a side elevation of a motor vehicle having my invention applied thereto.

In driving a motor vehicle, it is now required in many States, that the driver must signal his intentions of turning or stopping by holding the hand in certain designated positions just previous to the contemplated maneuver. At night time it is often very difficult to see the hand of the driver, particularly to a following machine, and applicant has provided a novel arrangement of lighting which lighting will fully illuminate the hand and arm of the signalling driver, without in any manner causing confusing rays of illumination which would be objectionable to any driver, either of the machine itself, or of an approaching machine.

In the accompanying drawing wherein for the purpose of illustration is shown a preferred embodiment of my invention, the numeral 5 designates a motor vehicle as a whole having a running board 6, front and rear fenders 7 and 8 respectively. The fenders on

the driver's side of the vehicle are pierced so as to provide openings into which reflectors in the form of pockets 9 and 11 are inserted; one reflector being in the front fender, and arranged at an upward and rearward angle adjacent to the juncture of the front fender with the running board and the other reflector being in the rear fender and arranged at an upward and forward angle at the juncture of the rear fender with the running board. It will be noted that the reflector or pocket 9 has its lower wall longer than its upper wall, and the reflector 11 has its upper wall longer than its lower wall. Within each of these reflectors is positioned a bulb as shown at 12 and 13, which bulb is connected to the battery of the car and the circuit is controlled by any convenient switch so that the lights will be illuminated only when desired; as for instance, during night driving.

In practice a glass lens is placed over the bulb to thus eliminate danger of water and dirt filling up the reflectors and short circuiting the bulbs. The result of this inserting of the reflectors and the lights within the fenders is that the bulb 12 will cause rays of illumination or beam of light to extend from the reflector 9 to the line X X as indicated in dotted lines while rays of illumination from the bulb 13 will cause rays of illumination to extend from the reflector 11 to the line X X as shown in dotted lines. As the line X X is substantially the path in which the operator will move his hand in signaling, it will be apparent that both the front and back of the hand and arm will be fully illuminated, and therefore, readily visible for a considerable distance, and that due to the annular placing of these reflectors the rays of illumination will not interfere with an on-coming vehicle.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:—

In means for illuminating the side of a vehicle body and the hand of the operator of the vehicle when projected outwardly and laterally for signalling purposes, comprising reflectors in the form of pockets set in the fenders on the said side of the vehicle with the upper edges of the pockets arranged flush with the upper surfaces of the fenders respectively, light bulbs arranged in the pockets, one pocket being disposed at an upward and rearward angle adjacent to the juncture of the front fender with the running board and having its lower wall longer than its upper wall and the other pocket being disposed at an upward and forward angle at the juncture of the rear fender with the running board and having its upper wall longer than its lower wall whereby two beams of light will be directed in converging relation to illuminate the side of the vehicle body and to intersect in a plane substantially in the path in which the operator will move his hand outwardly for signalling purposes.

In testimony whereof I affix my signature.

SAHN K. LOWE.
